UNITED STATES PATENT OFFICE

2,683,454

MASSAGER AND MANIPULATOR

Carl Brandenfels, St. Helens, Oreg.

Application October 14, 1952, Serial No. 314,701

8 Claims. (Cl. 128—58)

1

This invention relates generally to manipulating and massaging devices for use on the limbs, body and head of a human being and is specifically related to devices for "toning" up the tissues of the human body especially the scalp tissues.

This invention has also a close affinity to my United States Patent Number 2,657,686, dated November 3, 1953.

As stated in my co-pending application it is well known that hair, itself inert and consisting of the fibrous substance keratin, grows in tiny tubular shafts known as follicles which dot the scalp and penetrate into the scalp about half an inch. Each follicle forms a small "bulb" at its base, encasing a projection of tissue with tiny blood vessels called the papilla from which the hair draws its nourishment. Hair will continue to grow as long as the hair follicles remain undamaged, the follicle openings at the top of the scalp remain unimpaired and the hair roots receive a sufficient blood supply. The hair roots draw nourishment from several sources of blood supply going up into the scalp. Blood is furnished the scalp through the Y-shaped artery going up each side of the throat under the ears, one branch going behind the ears and up the scalp and the other branch going in front of the ears close to the ear lobes and up the scalp. Blood is also furnished the scalp through an artery going up the back of the neck from the shoulders to the scalp.

Blood is also furnished the scalp through sources passing through what are called the diploic blood vessels inside the spongy tissue of the skull bones and furnish blood mainly to the back top of the scalp and to the high part of the temple on either side. All of these blood supplies branch out into a network of very tiny blood vessels, called the capillary system, part of which nourish the hair follicles. Sebaceous gland ducts entering the hair follicles provide lubrication for both the scalp and hair and unless the hair roots are nourished by adequate blood supply and the openings at the scalp where the hair shafts emerge from the follicles are unimpaired, baldness usually results.

Baldness is largely caused by a diminution in mobility and tenseness in the scalp tissue usually caused by the stretching of the bony skull cap which compresses the blood vessels supplying the scalp and thereby impairing, if not entirely injuring, the cellular tissue and causing the degeneration of the hair follicles due to the lack of nutrition. Such a devitalized condition may be overcome by proper stimulation of the scalp and

2

the surrounding area of baldness, to induce the flow of an adequate supply of nutrients to the hair follicles.

It is the principal object of my invention to provide a device for the purpose of producing this stimulation by inducing an upwardly moving adequate supply of blood to the regions where the hair roots have not been completely destroyed and to restore circulation of this blood in the capillary system and to relieve tension in the scalp tissues.

Another object of my invention is to provide a device for inducing artificial and lasting erythema by a dilation of the vascular system in the area under stimulation without detrimental abrasive friction tending to break down the tissue or vascular system.

Another object of my invention is to provide a device for stimulating the area being treated and immediately ahead by a smooth flowing pressure coordinated with the normal heart beat which flushes blood under pressure greater than normally pumped by the heart, and without causing the skin to crawl in the process.

Still another object of my invention is to provide a compactly designed and simplified device which may also readily be employed to stimulate different portions of the human body regardless of the contours involved.

A further object of my invention is to permit the use of different types of massaging and stimulating roller assemblies for special type of massaging and stimulating and making it possible to readily employ such assemblies by their easy removal from and replacement on the device.

Another object of the invention is to provide a device which permits the removal and replacement of the roller assemblies for cleaning, in order to maintain hygienic conditions.

Still another object of the invention is to provide means for changing the normal position of the roller assemblies in order to allow the use of the device for massaging and stimulating any portion of the body.

Other objects and advantages and the novel features of my invention and its characteristics will be more readily understood from the detailed description which follows, taken in connection with the accompanying drawings forming part thereof, and in which:

Fig. 1 is an elevational view of the underside portion of the device embodying the invention;

Fig. 2 is a side elevation of the device embodying my invention and showing the two positions the roller assembly may assume;

Fig. 3 is a fragmentary top plan view taken

on line 3—3 of Fig. 2, showing the details of the jack member and stop elements;

Fig. 4 is a fragmentary elevation of the device embodying my invention showing a modified type of jack for the roller assembly;

Fig. 5 is an elevational view of a modified type of roller;

Fig. 6 is an elevational view of a modified type of roller; and

Fig. 7 is an elevational view of still another type of roller.

The structural details of the invention as revealed in the drawing which, by this reference, is made a part hereof, consist of a frame, designated generally by reference character A. The frame is fabricated from a single sheet of metal having inherent spring like qualities and consists of a top 1 and end walls 2 and 3. The end walls terminate in transversely positioned sockets 4 and 5 respectively, shown in Figure 2 in dotted line, each of which is adapted to receive and seat anchoring pins 6 and 7 respectively. The end walls 2 and 3 are relatively vertical and are joined to top 1 by gradually curving portions 8 and 9 respectively. The frame, as formed, together with the inherent flexibility of the material from which it is fabricated, gives the frame the resiliency necessary for its successful employment as a support for the massaging and stimulating elements of the device.

There is provided at each side of and as an integral part of the top 1 of the frame, downwardly extending grip elements 10 and 11 which reduce the flexibility of and reinforces the frame at this point in order to provide a substantial gripping surface and to prevent its bending from the thrust created by the extension of the jack member yet to be described. Secured in any desirable manner to the underside of the top 1 and confined between grip elements 10 and 11 is a catch 12, the function of which will become evident from the description which follows.

A plurality of links 13, possessing identical longitudinal measurements, are positioned in end to end relationship and hingedly connected to form a chain. A plurality of links 14, equal in number to and having the same structural characteristics as links 13, are also positioned in end to end relationship and hingedly connected to each other to form a chain. These articulated dual chains, possessing identical structural characteristics are joined to each other in spaced lateral relationship by a plurality of identical pins 15, each pin forming the connecting hinge between pairs of links 13 and 14 of each chain and thereby forms a single chain belt. A bushing 16, best shown in Figures 3 and 4, 5, 6, and 7 made of any desirable material having self-lubricating characteristics surrounds each pin and is freely rotatable in relation thereto. These bushings define the maximum spacing between the dual chains formed by the links 13 and 14.

Rollers 17, the length of which is slightly less than bushings 16, are fixedly mounted on the bushings so that the pins 15 act as shafts for the rollers. These rollers are spaced at well defined distances on the dual chain belt in order for them to apply pressure on the critical portions of the vascular system in coordination with the normal pulsation of the heart. Rollers 17 may be made of any yielding material, such as a synthetic substance possessing the characteristics of durability, lightness in weight and with any desired peripheral configuration provided the surface creates a minimum of frictional re-

sistance. The standard form of roller, as shown in Figs. 1, 2, 3 and 4 is cylindrical in cross section and has a smooth peripheral surface. It may also have a plurality of holes, as shown in Fig. 5, formed longitudinally therethrough to add to their massaging effectiveness and the peripheral surface may be fluted, as shown in Fig. 6, or may have a plurality of teats on its peripheral surface as shown in Fig. 7.

The pins 15 passing through the pairs of links 13 and 14 are fastened in rivet fashion at their free ends so that free but intimate movement is permitted at the link hinge joints.

The end links 13a and 14a are slightly wider than the remaining links 13 and 14 respectively and have anchor pins 8 and 7 transversely secured thereto midway between these links. Links 13b and 14b are also slightly wider than links 13 and 14 respectively and have jack member 18 hingedly secured therebetween in any desirable fashion. This jack member is positioned relative to the rollers 17 so that it does not contact the peripheral surface of the rollers or in any way affect their rotation. To insure against this possibility stop elements 19 and 20 extend inwardly from the top of links 13b and 14b respectively and limit the hinging movement of jack member 18 since it is positioned therebetween. When it is desired to change the normal position of the roller assembly as shown in full line, to the position as shown in dotted line, the end 21 of jack member 18 is fitted into the catch 12, as indicated by dotted lines in Fig. 2.

It should be noted, as indicated by the dotted lines, that the contour of the top 1 and end 2 of the frame A is also changed by the increased tension due to the placement of the jack member 18 into the position as shown in dotted lines.

The normal position of the roller assembly may be changed by other means, one of which is illustrated in Fig. 4, in which links 13c and 14c (not shown) have a pin 22 transversely secured thereto. Link 23 is hingedly secured thereto. Link 24 has one of its ends hingedly secured to the free end of link 23 and the other of its ends is hingedly secured to a pin 25 transversely positioned in relation to grip elements 10 and 11. A sleeve 26 is slidably positioned on link 24 and is adapted to fit over the hinge formed between links 23 and 24, when the links are positioned as indicated by the dotted lines in Fig. 4. When the roller assembly is in normal operating position, there is a knee action relationship between links 23 and 24, but when the sleeve is permitted to slide over the juncture between the two links in order to change the position of the roller assembly and increase the tension thereof, the knee action is entirely eliminated.

The roller assembly hereinabove described is removably anchored to frame A by setting the pins 6 and 7 in the transversely located sockets 4 and 5. The roller assembly is held in tensioned relation to the frame by the inherent flexibility of the material from which the frame is fabricated and the position of end walls 2 and 3 of the frame. Thus while the roller assembly is retained under tension, there is sufficient flexibility in the frame and the articulated construction of the chains to permit the rollers to follow the contour of any portion of the body to which the device may be applied. However, it may be desired to increase the tension of the roller assembly and to also change the normal position of the rollers in relation to the frame 75 in order to permit the massaging and stimulating

rollers to follow the contours of the body. This, of course, may be accomplished by the use of any one of the jack members heretofore described. It should be noted that a roller extends beyond the ends 2 and 3 of the frame A. By this construction no part of the frame can contact any portion of the body nor can the hair on the body be caught by any of the elements of the device.

Roller assemblies having rollers of the type shown in Fig. 5 or Fig. 6, or Fig. 7, may be employed in order to induce different forms of stimulation and massaging and since the roller assembly is removably anchored to the frame, the device may be provided with a multiple number of roller assemblies for the purpose of permitting the user to receive different modes of massage and stimulation.

A roller assembly having smooth rollers, with or without longitudinal holes therethrough, is made from material having inherent resiliency to insure against tissue damage by their movement over the body and is designed to squeeze quiescent blood in the capillaries and body tissue into the venous system of the body and allow the entrance therein of refreshed blood. That this occurs is evident from the exhilarating sensation felt on stimulation by massage.

A roller assembly having fluted rollers is made from similar material but has less resiliency than the smooth rollers and is designated to knead the fatty tissue during the massaging operation and permit this tissue to be carried off as body waste.

A roller assembly having a plurality of teats extending from its periphery is made from the same material as the smooth rollers and is designed to caress and penetrate between the wrinkles in the skin and to reach areas difficult to reach by the smooth roller and to excite the nerves adjacent to the skin surface to induce a tingling feeling of excitement at and adjacent to the area being massaged.

Although I have found in actual practice that the device as shown and described is efficient and satisfactory in operation, it is obvious that various changes may be made in the details of construction and arrangement of parts which will come within the scope of this invention, and therefore I do not wish to limit myself to the exact construction and arrangement herein shown, except as specified in the following claims, in which I claim:

1. In a device of the class described, a frame having springlike qualities as an inherent part thereof, a pair of grip elements extending from the top of the frame adapted to reduce the inherent flexibility of the frame at that point and providing a substantial gripping surface, a socket formed transversely of and at each end of the frame, a roller chain assembly removably secured to said frame in tensioned relationship thereto, and means secured to the roller chain assembly and removably engageable with the underside of the frame top for increasing this tension and changing the normal contour of the chain assembly.

2. In a device of the class described, a frame having springlike qualities as an inherent part thereof, a pair of grip elements extending from the top of the frame adapted to reduce the inherent flexibility of the frame at that point and providing a substantial gripping surface, a socket formed transversely of and at each end of the frame, a roller chain assembly removably secured to said frame in tensioned relationship thereto,

means secured to the roller chain assembly and removably engageable with the underside of the frame top for increasing this tension and changing the normal contour of the chain assembly, and stop members formed on the roller chain assembly to limit the movement of said means.

3. In a device of the class described, a frame having springlike qualities as an inherent part thereof, a socket formed transversely of and at each end of the frame, a roller chain assembly removably secured to said frame, said roller chain assembly comprising, a pair of transversely aligned chain belts joined together in spaced relationship, rotatable members supported between said chain belts, a pair of anchoring pins secured to said chain belts and adapted for being seated and anchored in the sockets formed in said frame to thereby hold the chains in tensioned relationship to the frame, said belts when so anchored being adapted to yield longitudinally in relation to the frame in order to allow the rotatable members to conform to the contour of the body as the device is moved over and pressed thereagainst.

10 4. In a device of the class described, a frame having springlike qualities as an inherent part thereof, a socket formed transversely of and at each end of the frame, a roller chain assembly removably secured to said frame, said roller chain assembly comprising, a pair of transversely aligned chain belts joined together in spaced relationship, rotatable members supported between said chain belts, a pair of anchoring pins secured to said chain belts and adapted for being seated and anchored in the sockets formed in said frame to thereby hold the chains in tensioned relationship to the frame, said belts when so anchored being adapted to yield longitudinally in relation to the frame in order to allow the rotatable members to conform to the contour of the body as the device is moved over and pressed thereagainst.

20 5. In a device of the class described, a frame having springlike qualities as an inherent part thereof, a socket formed transversely of and at each end of the frame, a roller chain assembly removably secured to said frame, said roller chain assembly comprising, a pair of transversely aligned chain belts joined together in spaced relationship, rotatable members supported between said chain belts, a pair of anchoring pins secured to said chain belts and adapted for being seated and anchored in the sockets formed in said frame to thereby hold the chains in tensioned relationship to the frame, said belts when so anchored being adapted to yield longitudinally in relation to the frame in order to allow the rotatable members to conform to the contour of the body as the device is moved over and pressed thereagainst, and means secured to the chain belts and removably engageable with the underside of the frame top for increasing this tension and changing the normal contour of said belt and roller assembly.

5. In a device of the class described, a frame having springlike qualities as an inherent part thereof, a pair of grip elements extending from the top of the frame adapted to reduce the inherent flexibility of the frame at that point and providing a substantial gripping surface, a socket formed transversely of and at each end of the frame, a roller chain assembly secured to said frame, said roller chain assembly comprising, a pair of transversely aligned chain belts joined together in spaced relationship, rotatable members supported between said chain belts, a pair of anchoring pins secured to said chain belts and adapted for being seated and removably anchored in the sockets formed in said frame to thereby hold the chains in tensioned relationship to the frame, said belts when so anchored being adapted to yield longitudinally in relation to the frame in order to allow the rotatable members to conform to the contour of the body as the device is moved over and pressed thereagainst, means secured to the chain belts and removably engageable with the underside of the frame top for increasing this tension and changing the normal contour of said belt and roller assembly, and stop members formed on the chain belts to limit the movement of said means.

6. In a device of the class described, a frame having springlike qualities as an inherent part

75

thereof, a pair of grip elements extending from the top of the frame adapted to reduce the inherent flexibility of the frame at that point and providing a substantial gripping surface; a socket formed transversely of and at each end of the frame, a roller chain assembly removably secured to said frame, said roller chain assembly comprising, a pair of transversely aligned chain belts joined together in spaced relationship, rotatable members supported between said chain belts, and a pair of anchoring pins secured to said chain belts immediately beyond each end roller and adapted for being seated and removably anchored in the sockets formed in said frame to thereby hold the chains in tensioned relationship to the frame, said belts when so anchored being adapted to yield longitudinally in relation to the frame in order to allow the rotatable members to conform to the contour of the body as the device is moved over and pressed thereagainst and to have a roller extending beyond the confines of the frame structure.

7. In a device of the class described, a frame having springlike qualities as an inherent part thereof, a pair of grip elements extending from the top of the frame adapted to reduce the inherent flexibility of the frame at that point and providing a substantial gripping surface, a socket formed transversely of and at each end of the frame, a roller chain assembly removably secured to said frame, said roller chain assembly comprising, a pair of transversely aligned chain belts joined together in spaced relationship, rotatable members supported between said chain belts, a pair of anchoring pins secured to said chain belts immediately beyond each end roller and adapted for being seated and removably anchored in the sockets formed in said frame to thereby hold the chains in tensioned relationship to the frame, said belts when so anchored being adapted to yield longitudinally in relation to the frame in order to allow the rotatable members to conform to the contour of the body as the device is moved over and pressed thereagainst and to have a roller extending beyond

the confines of the frame structure, and means secured to the chain belts and removably engageable with the underside of the frame top for increasing this tension and changing the normal contour of said belt and roller assembly.

8. In a device of the class described, a frame having springlike qualities as an inherent part thereof, a pair of grip elements extending from the top of the frame adapted to reduce the inherent flexibility of the frame at that point and providing a substantial gripping surface, a socket formed transversely of and at each end of the frame, a roller chain assembly removably secured to said frame, said roller chain assembly comprising, a pair of transversely aligned chain belts joined together in spaced relationship, rotatable members supported between said chain belts, a pair of anchoring pins secured to said chain belts immediately beyond each end roller and adapted for being seated and removably anchored in the sockets formed in said frame to thereby hold the chains in tensioned relationship to the frame, said belts when so anchored being adapted to yield longitudinally in relation to the frame in order to allow the rotatable members to conform to the contour of the body as the device is moved over and pressed thereagainst and to have a roller extending beyond the confines of the frame structure, and means secured to the chain belts and removably engageable with the underside of the frame top for increasing this tension and changing the normal contour of said belt and roller assembly and stop members formed on the chain belts to limit the movement of said means.
